UNITED STATES PATENT OFFICE.

CHRISTOPHER WINKEL, OF CLEVELAND, OHIO, ASSIGNOR TO THE THEODOR KUNDTZ COMPANY, OF CLEVELAND, OHIO, A CORPORATION OF OHIO.

SEAT DESK.

Application filed February 26, 1921. Serial No. 448,150.

To all whom it may concern:

Be it known that I, CHRISTOPHER WINKEL, a citizen of the United States, residing at Cleveland, in the county of Cuyahoga and State of Ohio, have invented a certain new and useful Improvement in Seat Desks, of which the following is a full, clear, and exact description.

One object of the invention is to provide simple, durable and easily manipulated mechanism for so supporting a desk or table that it may be moved in various directions and into many positions by and for the convenience of different users, and without danger that any part of the person sitting in a chair behind the table will be pinched or bruised, when the table is moved to or from the various positions it may occupy. Another object is to prevent the easy displacement of the table, through accident or mischievous intention either from the substantially horizontal operative position, or the turned up out-of-the-way position.

The invention consists in the construction and combination of parts shown in the drawing as herein described and definitely pointed out in the appended claims.

In the drawings, Fig. 1 is a side elevation of a desk chair which embodies the invention, viewed from the left side thereof; Fig. 2 is a plan view thereof; Fig. 3 is a side elevation from the right side of said desk-chair. Fig. 4 is a front elevation of said desk-chair with some of the parts broken away, and shown in vertical section. All of the foregoing figures shown the desk-chair when the table is in operative or usable position. Fig. 5 is a front elevation when the table has been turned up out of the way, and Fig. 6 is an enlarged sectional view in the plane of line 6—6 on Fig. 4.

This invention is most useful when the table supporting means are permanently attached to a chair and are located adjacent at one side of said chair and slightly in advance thereof, thereby producing what is known in the trade as a chair-desk, as shown in the drawing; but the novel features are to be found in the means for supporting the table upon a standard, so that said table shall be capable of being moved to and held in various positions.

The chair represented by 10 may be of any suitable construction. The desk or table 15 is adjustably supported, through mecha-

nism in which the present invention is embodied, on a vertical standard 21 which is secured to the chair at the front right hand corner thereof,—said standard being located in advance of the chair seat 14, and having its lower end extend down to engage the floor, and thereby serve as the right hand front leg 12 of the chair. An extension member is mounted to slide vertically on this standard and may be secured thereto at any desired elevation. This extension member comprises a metal plate 22 which is placed against the outer, i. e., right hand, face of the standard, and is provided with flanges 23 which engage with the front and rear edges of said standard; and a clamping plate 24 which is placed in contact with the inner face of the standard. Bolts 25 which pass through vertical slots 21^a in the standard 21, and hand nuts 26 thereon afford means for securing the extension at any desired elevation to the standard by drawing the plates 22, 24, toward one another and thereby clamping the standard between them.

The mechanism for supporting the table or desk 15 is carried by the extension member and goes up and down with it. The mechanism by which the table is supported permits it to be moved horizontally forward and backward, and to be tilted about a horizontal axis which extends transversely, and also to be swung about a horizontal axis which is at right angles to the tilting axis whereby it may be in operative position in front of the chair or may be swung up to a substantially vertical position out of the way of a person who desires to sit in or get out of the chair.

The specific mechanism shown in the drawing for endowing the table with the capacity to move as stated is as follows: The upper ends of the two flanges 23 are slightly prolonged upward and serve as ears 27. A horizontal shaft 28 is mounted in these ears and extends between them, and is prolonged in front of the front ear. Suitable means are preferably provided for preventing the shaft from moving endwise in these ears. This result may be attained by driving the shaft tightly into the holes in the ears; or it may be produced by any other suitable means. A sleeve 34 is fixed to one end of a bracket 30 and embraces and is slidable upon this rock shaft between the

two ears 27; and the bracket extends from said sleeve transversely in front of the chair. The table or desk 20 is secured to this bracket 30 by means which will be presently described. But it is obvious that by the turning of the sleeve 34 upon shaft 28 the table may be made to occupy either of the positions in which it is shown in the drawing.

10 While the construction shown is, as has been described, such that the sleeve 34 turns upon and slides along the shaft 28, it is of course obvious that the essential thing is that the table shall be capable of moving 15 lengthwise of the shaft and of swinging about the axis of the shaft. The specific construction as described is preferred not because it has any functional advantages over other constructions by which the stated movements could be secured; but because it is somewhat cheaper than any other construction I have thought of.

15 The bracket 30 is in the form of a hollow cylinder, and it is provided with a rigid depending arm 32 near its supported end in such position that when the cylindrical portion occupies a substantially horizontal position, the depending bracket arm 32 will engage the clamping plate 24 and thereby support the bracket in the stated position, as best shown in Fig. 4. This bracket 30 is formed with two ears 33 on one end which ears tightly embrace the sleeve 34, and consequently embrace the shaft 28. The sleeve 34, as stated, lies between the ears 27, although the length of the sleeve is substantially less than the distance between the ears 27, so that said sleeve may move several inches forward and backward upon the shaft, said movement being limited by the engagement of the sleeve with one or the other of the ears 27.

20 In the construction shown the arm 32 of the bracket 30 is made of pressed metal, bent into U-shape, and formed with two arms 32^a which lie against the sides of the cylindrical part of the bracket, and are welded or otherwise secured rigidly thereto. And this bent metal piece may be formed with ears 32^b, which also tightly embrace the sleeve 34, and thereby reinforce and strengthen the connection between it and the bracket.

25 The table or desk 20 is associated with two bars 40 which extend forward and backward and are secured to its under side at a proper distance apart. A short cylinder or disk 38 is rotatably mounted in each end of the cylindrical portion of the bracket 30. Each of these disks 38 is provided with an upwardly extended arm 39 which is rigidly fixed to the adjacent bar 40,—said arms 39 passing through arcuate notches 30^d in the ends of the cylindrical part of the bracket. One of these disks 38, at least, carries a bolt 41 which passes through a circumferential slot

37 in the cylindrical wall of bracket 30, and it has a thumb nut 42 on its outer end which when screwed up will clamp the disk 38 immovably in the cylinder.

30 The desk may be moved horizontally toward or away from the occupant of the chair by causing the sleeve 34 to slide on shaft 28. Likewise the desk may be tilted to a considerable extent, which movement is permitted by the turning of the disks 38 in the ends of the cylindrical part of the bracket. When it is tilted to the position desired it will be clamped in that position by turning up the thumb nut 42.

35 When the desk is not in use it can be turned about the axis of shaft 28 and swung into the substantially vertical position shown in Fig. 4. There will then be nothing in front of the chair, and therefore a person may get to and from the chair as easily as if there were no desk attachment thereto. When, however, it is desired to use the desk it is turned down to the position shown in Fig. 4, at which time the arm 32 of the bracket engages the clamping plate 24 and holds the desk in substantially the position shown.

40 It is desirable that when the table is in a horizontal position, a mischievous scholar in the associated chair shall not be able to easily vibrate the table up and down and thereby cause the arm 32 to tap noisily against the clamping plate 24. It is likewise desirable that when the table has been turned up to the position shown in Fig. 5, it can not be easily pushed from that position so that it will swing to a horizontal position and cause arm 32 to bang against the clamping plate.

45 Both of these results are attained by means of a spring clamping plate 55 which along its lower edge is fixed to the standard extension 22, and has a bead 56 along its upper edge, for engagement in one or the other of the notches 30^e or 30^f in the peripheries of the ears which embrace the sleeve 34. This spring plate 55 will yield if a sufficient force is applied to the table to turn it about the axis of shaft 28, but it will prevent a slight push whether accidental or intentional on the table when in the position shown in Fig. 5, from starting to swing downward; and it will prevent one from vibrating the table up and down when it is in a horizontal position.

50 45 represents a shield which embraces the arm 32 of the bracket and is pivoted thereto and is preferably made of bent sheet metal. It is free to swing upon its pivot 46, and is so shaped that the action of gravity will cause it always to hang downward from its pivotal support into contact with the clamping plate 24. The chief purpose of this shield is to protect the occupant of the chair from getting any part of his person or

clothes caught between the end of arm 32 and the plate 24; and it performs this function because it always hangs down in contact with plate 24 regardless of the position of the table. This shield also hides from view some of the described mechanism, and also prevents oil or dirt from dropping from said mechanism onto the clothes of one sitting in the chair.

10 50 represents an inkwell holder by which an inkwell 51 is supported beneath a pen hole 17 in the table top,—through which hole a pen may be passed to the inkwell. The inkwell holder is slidably supported 15 upon shaft 28, but in such wise that the inkwell holder may not turn on the shaft.

As shown the inkwell holder includes a bar 52 which extends over and is in substantial contact with the front ear 27, and has 20 two downwardly extended ears 53 which loosely embrace shaft 28, one of them also embracing sleeve 34. The rear ear 53 projects between the front ear 45^a of the shield 45, and a collar 34^a on the sleeve 34. This 25 compels the inkwell holder to move forward and backward with the table, and thereby always preserves the necessary relation with the hole in the table top, but the engagement of the inkwell holder top bar 52 with the top 30 of the front ear 27 prevents the inkwell holder from turning about the axis of shaft 28.

Having described my invention, I claim:—

35 1. In an adjustable table, the combination of a standard, a horizontal shaft mounted on the upper end of said standard, a bracket supported at one end by said shaft and provided with a depending arm for engagement with the standard when the bracket is in horizontal position,—said bracket being capable of turning about the axis of said shaft and of moving in the direction of the axis of said shaft, table supporting means 40 pivoted to said bracket on a transverse horizontal axis, a table fixed to said table supporting means, and means to secure said table supporting means to the bracket in any desired position relative thereto.

50 2. In an adjustable table, the combination of a chair and a standard secured thereto and provided with a vertically adjustable upper end, a horizontal shaft mounted on the upper end of the standard, a bracket 55 having a horizontal arm which at one end embraces and is supported by said shaft and is movable about the axis of said shaft and parallel with the axis of said shaft, said bracket being provided with a downwardly extended arm adapted to engage with the standard when said bracket is in the horizontal position, the horizontal part of said bracket being in the form of a hollow cylinder, short cylinders which are rotatably mounted in the ends of said cylindrical arm

and have each an upwardly projecting arm, a table, two bars rigidly secured to the under side thereof and respectively fastened to said upwardly extended arms of said short cylinders.

70

3. In an adjustable table, the combination of a standard having a vertically adjustable upper end, a horizontal shaft mounted on the upper end of the standard, a bracket having a horizontal arm which at one end is supported by said shaft through means which permit the bracket to turn about the axis of and lengthwise of the axis of said shaft, and which is provided with a downwardly extended arm adapted to engage with the standard when said bracket is in the horizontal position, the horizontal part of said bracket being in the form of a hollow cylinder, short cylinders which are rotatably mounted in the ends of said cylindrical arm and are each provided with an upwardly projecting arm, the cylinder having circumferential notches through which the arms attached to said short cylinders project,—a table, two bars rigidly secured to the under side thereof and respectively fastened to said upwardly extended arms of said short cylinders, a bolt secured to one of said short cylinders and passing through an arcual slot in said cylindrical arm, and a thumb nut screwed onto the outer end of said bolt.

85

90

95

4. In an adjustable table, the combination of a standard having at its upper end a pair of ears, a shaft which goes through and is supported by said ears, a bracket which at one end has a supporting connection with said shaft, the said bracket being capable of turning about the axis of said shaft, a downwardly extended arm fixed to said bracket for engaging said standard when the main arm of the bracket is in horizontal position, a table which is mounted on the main arm of said bracket by means which permit the table to be tilted about a horizontal transversely extended axis, and a shield which embraces the downwardly extended arm of said bracket and is loosely pivoted near its upper end to said bracket whereby the shield will always hang vertically downward and will engage with the standard while the bracket is being turned about the axis of said shaft, and a table connected with and supported by the horizontal arm of said bracket.

100

105

110

115

120

5. In an adjustable table, the combination of a chair and a standard secured thereto, with a horizontal shaft mounted on the upper end of said standard, a bracket, means which establish a supporting connection between the shaft and one end of the bracket, a depending arm fixed to said bracket for engagement with the standard when the bracket is in horizontal position, and a table connected with and supported by said

125

130

bracket, and a downhanging shield which is freely pivoted to said bracket near its supported end and which embraces the depending arm thereof and engages the standard.

5 6. In an adjustable table, the combination of a standard, with a horizontal shaft mounted on the upper end of said standard, a bracket supported at one end by said shaft and provided with a depending arm
10 for engagement with the standard when the bracket is in horizontal position, said bracket being capable of turning about the axis of said shaft and of moving in the direction of the axis of said shaft, a table
15 which is provided with a pen hole and is connected with and supported by said bracket, and an inkwell holder supported on said shaft, means to prevent the inkwell holder from turning about the axis of said shaft, and means compelling the inkwell holder to move lengthwise of the shaft in
20 unison with the bracket.

7. In a combined desk and chair, the combination of a chair, a standard secured thereto having a vertically adjustable upper end, a horizontal shaft which is connected with the upper end of the standard, a bracket, means which connect one end of the bracket with the shaft and permit the bracket to turn about the axis of the shaft and to move lengthwise of the shaft, an arm fixed to said bracket for engagement with the standard to prevent the bracket from swinging below a substantially horizontal position, a table which is pivotally connected with said bracket on a transverse axis, and means to lock the table to the bracket.

8. In an adjustable table, the combination of a standard, a table, a bracket upon which the table is secured, said bracket being pivotally connected with the standard on a horizontal axis, means to limit the swinging movement of the table below a substantially horizontal position, and means engageable with the bracket for yieldingly holding said table in its operative position or in its inoperative substantially vertical position.

9. In an adjustable table, the combination of a standard, a horizontal shaft which is secured to the upper end of said standard, a bracket having ears at one end which embrace said shaft,—which bracket is capable of turning about the axis of the shaft,

a table secured to said bracket, means to prevent the table from swinging below a substantially horizontal position, a spring latch engaging with the periphery of an ear on said bracket,—said ear being provided with two notches for the engagement 60 of said spring latch.

10. In an adjustable table, the combination of a standard having a vertically adjustable upper end which is provided with two upwardly extended ears, a cylindrical 65 shaft which passes through and is supported by said ears, a bracket having at one end a sleeve which is slidably mounted upon said shaft between the ears which support said shaft,—said bracket being capable of 70 turning about the axis of the shaft, an arm fixed to said bracket for engagement with said standard to prevent the table from moving below a substantially horizontal position.

11. In an adjustable table, the combination of a standard having a vertically adjustable upper end which is provided with two upwardly extended ears, a cylindrical shaft which passes through and is supported 80 by said ears, a bracket having at one end a sleeve which is slidably mounted upon said shaft between the ears which support said shaft said bracket being capable of turning about the axis of the shaft, an arm 85 fixed to said bracket for engagement with said standard to prevent the table from moving below a substantially horizontal position, said bracket being provided with ears which tightly embrace said sleeve,— 90 one of said ears being provided with peripheral notches, and a spring latch fixed to the standard for engagement with said notches to yieldingly hold said table in its two extreme positions.

12. In an adjustable table, a standard, a horizontal shaft mounted on the upper end of the standard, a table pivoted upon said shaft and slidably lengthwise thereof, said table being provided with a penhole, an 100 inkwell holder slidably supported on said shaft and movable with the table lengthwise of the shaft, and means to prevent the inkwell holder from turning about the axis of the shaft.

In testimony whereof, I hereunto affix my signature.

CHRISTOPHER WINKEL.
